(57) **CLAIM**

The ornamental design for a jewelry item with spikes, as shown and described.

DESCRIPTION

FIG. 1 is a perspective view of a jewelry item with spikes;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of a jewelry item with spikes;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of a jewelry item with spikes;

FIG. 16 is a front view thereof;

FIG. 17 is a back view thereof;

FIG. 18 is a left view thereof;

FIG. 19 is a right view thereof;

FIG. 20 is a top view thereof;

FIG. 21 is a bottom view thereof;

FIG. 22 is a perspective view of a jewelry item with spikes;

FIG. 23 is a front view thereof;

FIG. 24 is a back view thereof;

FIG. 25 is a left view thereof;

FIG. 26 is a right view thereof;

FIG. 27 is a top view thereof;

FIG. 28 is a bottom view thereof;

FIG. 29 is a perspective view of a jewelry item with spikes;

FIG. 30 is a front view thereof;

FIG. 31 is a back view thereof;

FIG. 32 is a left view thereof;

FIG. 33 is a right view thereof;

FIG. 34 is a top view thereof;

(Continued)

FIG. 35 is a bottom view thereof;
 FIG. 36 is a perspective view of a jewelry item with spikes;
 FIG. 37 is a front view thereof;
 FIG. 38 is a back view thereof;
 FIG. 39 is a left view thereof;
 FIG. 40 is a right view thereof;
 FIG. 41 is a top view thereof;
 FIG. 42 is a bottom view thereof;
 FIG. 43 is a perspective view of a jewelry item with spikes;
 FIG. 44 is a front view thereof;
 FIG. 45 is a back view thereof;
 FIG. 46 is a left view thereof;
 FIG. 47 is a right view thereof;
 FIG. 48 is a top view thereof;
 FIG. 49 is a bottom view thereof;
 FIG. 50 is a perspective view of a jewelry item with spikes;
 FIG. 51 is a front view thereof;
 FIG. 52 is a back view thereof;
 FIG. 53 is a left view thereof;
 FIG. 54 is a right view thereof;
 FIG. 55 is a top view thereof; and,
 FIG. 56 is a bottom view thereof.

The broken lines shown in the drawings illustrate portions of the jewelry item that form no part of the claimed design.

1 Claim, 24 Drawing Sheets
